(57) **CLAIM**

The ornamental design for an electronic connector set, as shown and described.

DESCRIPTION

FIG. 1 is a top and front perspective view of a male connector of the electronic connector set showing our new design;

FIG. 2 is a top and back perspective view of a male connector thereof;

FIG. 3 is a front elevational view of a male connector thereof;

FIG. 4 is a rear elevational view of a male connector thereof;

FIG. 5 is a left side elevational view of a male connector thereof;

FIG. 6 is a right side elevational view of a male connector thereof;

FIG. 7 is a top plan view of a male connector thereof;

FIG. 8 is a bottom plan view of a male connector thereof;

FIG. 9 is a top and front perspective view of a female connector of the electronic connector set showing our new design;

FIG. 10 is a top and back perspective view of a female connector thereof;

FIG. 11 is a front elevational view of a female connector thereof;

FIG. 12 is a rear elevational view of a female connector thereof;

FIG. 13 is a left side elevational view of a female connector thereof;

FIG. 14 is a right side elevational view of a female connector thereof;

FIG. 15 is a top plan view of a female connector thereof;

FIG. 16 is a bottom plan view of a female connector thereof;

FIG. 17 is a top perspective view of both the male and female connectors of the electronic connector set; and,

FIG. 18 is a top and side perspective view of both the male and female connectors of the electronic connector set.

The broken lines shown represent portions of the electronic connector set and form no part of the claimed design.
